UNITED STATES PATENT OFFICE.

EARL R. PIERCE AND ERNEST E. PIERCE, OF SHELBY, MONTANA.

ANKLE BRACE.

Application filed June 13, 1925. Serial No. 36,969.

This invention relates to ankle braces such as are used by skaters but also adaptable for use under other circumstances.

The general object of the invention is to provide an ankle brace which is simple, strong, thoroughly effective for the purpose intended, and yet which will give the desired amount of flexibility to the ankle and permit the foot to be flexed with relation to the ankle.

A further object is to provide a device of this character which, by an interchanging of parts, is adapted to a great many different circumstances of use.

15 Our invention is illustrated in the accompanying drawings, wherein:—

Figure 1 is a perspective view of one form of ankle brace constructed in accordance with our invention;

20 Figure 2 is a fragmentary vertical sectional view thereof;

Figure 3 is a perspective view of another form of heel plate showing the portion 10;

25 Figure 4 is a section on the line 4—4 of Figure 3;

Figure 5 is an elevation of another form of heel plate and slide;

30 Figure 6 is a section on the line 6—6 of Figure 5, the tang being shown in dotted lines;

Figure 7 is a rear elevation of the construction shown in Figure 8;

35 Figure 8 is a section on the line 8—8 of Figure 5.

Referring to the construction shown in Figures 1 and 2, it will be seen that the ankle brace consists of the vertically extending tang or shank 10 which is made of relatively thin but stiff, resilient metal. The upper end of this tang 10 is formed with a transverse portion 11 and this T-shaped upper portion of the tang 10 is enclosed within a semi-circular leather pad 12 formed in two pieces stitched together, as at 13. Also passing through this pad and adapted to pass around the leg is an upper strap 14 having a buckle 15 and a lower strap 16 having a like buckle.

40 Adapted to be connected to this tang 10 is any one of a number of shoe-engaging members. In Figure 3 we illustrate a very simple form of shoe-engaging member consisting of a curved metal yoke 17 adapted to partially embrace a heel and be attached thereto by means of the transverse bolt 18,

this metal plate having an upwardly extending portion 19 adapted to lie flat against the shank or tang 10 and formed with the inturned flanges 20 constituting a guide and fitting tightly against the shank 10 so that this member 19 may slide up and down upon this shank 10. This construction will brace the ankle and prevent any free pivotal movement of the foot with relation to the ankle but at the same time will permit the heel to move vertically with relation to the brace 10 and the elasticity of the brace will permit a slight flexing of the ankle.

In Figure 1 we show another shoe-engaging attachment comprising a slide 21 having inturned flanges 22 adapted to fit upon and slide on the tang 10. This slide at its lower end is formed with the hinge bead 23 which engages a pintle 24 which passes through hinge beads 25 formed in the upper end of a heel plate 26 which extends downward and partially embraces the heel A and to which it is fastened either by screws or by a transverse bolt such as the bolt 18. This construction permits the foot to move vertically relative to the brace but also permits a flexing of the foot at the ankle joint.

In Figures 5 to 8 we illustrate still another form which is comparable to the construction shown in Figure 1 and comprises the heel plate 27 formed at its lower end to partially embrace the heel and be attached thereto, as by means of a bolt or screw, as previously described, this heel plate being enlarged at its upper end and formed to provide two hinge beads 28. Pivoted upon the pintle 29 of this plate is a slide plate 30 which is formed at its four corners with outwardly projecting lugs 31. Opposed exteriorly to the ends of this sliding plate are transverse bars 32, and disposed between these bars at the corners of the slide plate opposite the lugs 31 are the grooved rollers 33 which engage the edges of the tang. This construction is the same in general effect as that shown in Figure 1 but the grooved rollers permit a readier sliding action of the slide plate 30 upon the tang 10.

The ankle brace as described has been found by us to be particularly effective for use in skating where the skater's ankles are weak and liable to turn, but it is also eminently adaptable for permanent cripples or for use in other circumstances. The brace braces the ankle against any tendency to turn

but at the same time gives ample flexibility to the ankle joint to permit the usual flexing of the foot and ankle joint.

While we have illustrated certain details of construction and arrangement of parts which we believe to be particularly effective, we do not wish to be limited to this as it is obvious that many changes might be made without departing from the spirit of the invention as defined in the appended claims.

The construction shown in Figure 1 is probably the preferable construction for skating because it is simple, light, strong and permits sufficient freedom of movement for all ordinary skaters and can be economically constructed. The heel engaging member shown in Figure 3 works in the manner of a hinge upon the bolt 18 and this allows a forward and backward movement of the leg, and where the heel engaging member is hinged it allows the heel to have a downward and forward movement or upward and rearward movement with respect to the ankle in the arc of a circle as the toe is raised and lowered respectively. The hinge further allows the slide and tang to work together without unnecessary friction which would be caused by forcing the tang through the slide when the tang is bent.

The heel engaging members shown in Figures 5 to 8, while they will cost more in actual construction, will wear longer and work more smoothly and are better adapted for wear by persons with weak or crippled ankles. Furthermore, this type permits oiling more readily than the type shown in Figure 1. It is to be understood that the combination of the forms shown in the several figures might be used especially for use where the ice is soft and flakes collect on the shoe heel and soften the leather which would thus permit screws, if used, to become loose or torn out. It is also to be understood that the tang may be curved so as to fit closely around the back of the heel and it is to be understood that the parts of this brace may be entirely or partially enclosed in soft leather or fabric. These braces make it possible for women or men with weak ankles to learn to skate. The device can be attached to the heel of the shoe or to the skate to hold the skate in as near a vertical position as may be desired when the wearer is in an upright position. The tang will prevent any tipping of the skate to either side.

We claim:—

1. An ankle brace of the character de-

scribed comprising a transversely flat tang of resilient metal having means at its upper end whereby it may be bound upon the leg, the tang extending downward from said means, and a shoe heel engaging member slidably engaged with the tang and including a flat plate-like member overlapping the tang and having sliding contact therewith.

2. An ankle brace of the character described comprising a vertically extending transversely flat tang having means at its upper end whereby it may be engaged with a leg, the tang being of resilient metal, a flat slide slidably mounted upon the tang and bearing flat against the face of the tang, and a shoe heel engaging plate hingedly engaged with said slide, the plate at its lower end being laterally extended and curved to partially embrace the heel and be attached thereto.

3. An ankle brace of the character described comprising a tang having a cross piece at its upper end transversely curved to fit the leg, a pad within which the cross piece and the upper portion of the tang are enclosed and having straps whereby it may be bound upon the leg, the tang being of transversely flat resilient metal, and a heel-engaging member including a transversely flat plate bearing flat against said tang and having sliding engagement with the tang.

4. An ankle brace of the character described comprising a tang having a pad at its upper end and curved to partially embrace the leg and having straps whereby it may be bound upon the leg, the tang being of resilient metal, a slide engaging the tang and carrying grooved rollers bearing against the side edges of the tang, and a heel plate hingedly engaged with the lower end of the slide and having means whereby it may be engaged with the shoe heel.

5. An ankle brace of the character described comprising a tang having means at its upper end whereby it may be bound upon the leg, the tang extended downward from said means and being slightly resilient and transversely flat, a slide engaging the tang and carrying laterally disposed grooved rollers bearing against the side edges of the tang, and a heel plate hingedly engaged with the lower end of the slide, and having means whereby it may be engaged with the shoe heel.

In testimony whereof we hereunto affix our signatures.

EARL R. PIERCE.
ERNEST E. PIERCE.
